UNITED STATES PATENT OFFICE.

EPHRAIM McCLOY, OF BROOKLYN, NEW YORK.

SPARK-PLUG.

1,295,337.

Specification of Letters Patent. Patented Feb. 25, 1919.

Application filed December 29, 1917. Serial No. 209,511.

To all whom it may concern:

Be it known that I, EPHRAIM McCLOY, a subject of the King of Great Britain, residing at Brooklyn, in the county of Kings 5 and State of New York, have invented new and useful Improvements in Spark-Plugs, of which the following is a specification.

This invention relates to spark plugs for internal combustion engines and has for its 10 principal object, the provision of a priming tube serving as one terminal and provided adjacent to the other terminal of the plug with a flared spark augmenting and deflecting passage whose walls are associated 15 with said other terminal whereby to produce an annular spark gap between both terminals.

Another object of the invention resides in the provision of a tubular terminal flared 20 at the gap end of the plug and associated with the other terminal whereby to produce a downward and lateral discharge of the spark and greatly increase the size of the spark area and positively assure an ignition 25 of the explosive charge thereby.

A still further object of the invention is to provide a spark plug which will have coupled with an idea of simplicity and durability, an arrangement of spark terminals 30 which will be of a self cleansing character incident to their peculiar formation and relation to one another.

With the above and other objects in view which will appear as the nature of the invention is better understood, the same consists in the improved construction and novel arrangements of parts which will herein-after be fully described and particularly pointed out in the claims.

40 In the accompanying drawings, has been illustrated, a single and preferred form of the invention, it being, however, understood that no limitations are necessarily made to the precise structural details therein exhibited, but that changes, alterations and modifications within the scope of the claims may be resorted to when desired.

Figure 1 is a side view of the plug.

Fig. 2 is a vertical section therethrough 50 with parts in elevation.

Fig. 3 is a transverse section on line 3-3 of Fig. 2.

Fig. 4 is a transverse section on line 4-4 of Fig. 2.

55 The device consists of a metallic body

member 5, threaded at its lower end, for connection with the cylinder of an internal combustion engine. The said member is provided with a central passage 6, through which a porcelain member 7, extends, said 60 member having a continuous bore 8, therein through which a tubular terminal 9, extends. The said tubular terminal is extended beyond the upper end of the member 7, and the same is threaded at 10, for operative connection with a priming cup 11, having a valve 12, which is adapted to be opened manually or in any other suitable well known manner, so as to establish communication between the cup and the bore 13, of 70 the mentioned terminal 9. The bore 8, of the member 7, which receives said terminal is flared outwardly as at 14, at its lower end to accommodate itself to a correspondingly flared end 15, of said terminal 9. In this 75 manner, a gap pocket or space 16, is produced whose diameter increases in a downward direction. The second terminal 17, of the plug is connected at one end to the metallic member 4, and is curved downwardly 80 therefrom at 18, and from this portion, it is provided with a vertical substantially pointed branch 19, which extends into the flared lower end of the terminal 9, and is positioned axially of the space 16. In this 85 way, it is observed that an annular spark gap is produced between the flared walls of the terminal 9, and the branch 19, of the other terminal 17. The minimum diameter of the space or pocket 16, is sufficiently 90 calculated with respect to the branch 19, of said terminal 17, so as to prevent the priming fluid from closing the gap between both terminals so as to positively prevent short circuit as will be understood. When gaso- 95 lene or the like is placed in the priming cup, a desired portion thereof can be discharged into the bore of the terminal 9, where it will flow to the spark gap and be divided and in a manner atomized at the meeting point 100 of the two terminals of the plug. As a consequence thereof, it will be observed that on the production of a spark, the priming fluid will be promptly ignited and the fire produced by the spark will be scattered in a 105 relatively broad manner from the base of the plug in the direction of the explosive chamber of the engine. This manner of igniting the fire and at the same time producing an annular spark gap with means for deflecting 110

the same downwardly and laterally, always insures a satisfactory ignition of the explosive charge.

The suction induced in the pocket or space 5 16, at the time of an explosion, operates to always clear the terminals of the plug and positively prevent carbon from accumulating and adhering thereto. From practice, it is found that the more the plug is used, the more the two terminals at the spark 10 gap are cleansed incident to this peculiar action.

What is claimed as new is:—

1. A spark plug comprising a metallic body, a porcelain core extending therethrough, a tube extending axially through said core, a priming cup threaded upon the upper end of said tube and bearing against the end of said core, the lower end of said 15 20 tube being flared, and a terminal member

connected with said body at its lower end and reflexly bent to have its other end extending within the flared end of said tube.

2. A spark plug comprising a metallic body, a core of insulating material extending therethrough, a tube extending axially through said core and having its lower end flared and terminating flush with the lower ends of said body and core, the upper end of said tube extending beyond the upper 25 30 end of said core and being threaded, a priming cup engaged upon the upper end of said core, and a contact terminal secured at one end of said shell and having its free end reflexly bent and extending into the flared end of said tube, said inwardly projecting end of said terminal being pointed.

In testimony whereof I affix my signature.

EPHRAIM McCLOY.
